UNITED STATES PATENT OFFICE.

WALTER CALEB THATCHER, OF GOVANS, BALTIMORE, MARYLAND.

LATHE.

Application filed May 16, 1923. Serial No. 639,369.

To all whom it may concern:

Be it known that I, WALTER CALEB THATCHER, a citizen of the United States, and a resident of Govans, Baltimore, in the 5 State of Maryland, have invented certain new and useful Improvements in Lathes, of which the following is a specification.

This invention relates to lathes designed for metal working and is more particularly 10 directed to a lathe for turning and boring castings or patterns employed in the manufacture of hats.

Elliptical patterns employed in the manufacture of straw hats as now commonly used 15 are whittled by hand. From these patterns molds are made in sand for casting a plurality of shapes from spelter or aluminum or other metals suitable for the purpose. The castings are then polished on buffing wheels 20 or scraped. By this means it is difficult to obtain shapes which are accurate in every detail.

It is an object of my invention to provide a device for automatically and mechanically 25 producing elliptical metal forms which may be turned out in quantities and which are accurate in every detail.

A further object of the invention is the provision of a device having an oscillating 30 frame for producing elliptical metal forms and which frame may be locked in place for converting said device into a vertical chucking machine for boring or turning the usual circular or cylindrical forms.

35 Other objects and advantages will become apparent during the course of the following description.

The invention is illustrated by way of example in the accompanying drawings, in 40 which,

Figure 1 is a side elevation of my improved lathe.

Figure 2 is an end elevation of the same.

Figure 3 is a horizontal section taken 45 along the line 3—3 of Figure 1.

Figure 4 is a longitudinal view of a driven shaft mounted upon an oscillating table.

Figure 5 discloses a plan view and a sectional view of a block formed of wood or 50 plaster.

Figure 6 is a sectional view of a metal block.

Figure 7 shows a plan view and a sectional view of a head plate.

55 Figure 7^a is a vertical section of a head plate.

Figure 8 is a sectional view of a head plate interfitting with the head plate shown in Figure 7^a.

Figure 9 is a plan view and a sectional view of an elliptical pattern cam.

Figure 10 shows a plan view and a sectional view of a hydraulic pattern and interfitting ring.

Referring more particularly to the drawings, 1 and 2 designate side members of a frame which are connected together by the spaced tracks 3 and 4.

Slidably mounted on the tracks 3 and 4 is a vertically disposed table 5 provided with aligned bearings 6 which are adapted to receive the driven shaft 7 which is shown more in detail in Figure 4. The shaft is provided adjacent its end with annular flanges 8 and 9. The extreme opposite ends of the shaft are feathered as shown at 10 and 11. Upon one end of said shaft and locked to the shaft for simultaneous rotation by the feather 10 and a set screw 10^a is a face plate 12. Upon the opposite end 80 of the shaft and locked to said shaft for simultaneous rotation by means of the feather 11 and a set screw 11^a is an eccentric or pattern cam 13. This cam is replaceable by other cams of various shapes for causing 85 variations in the work produced.

A roller 14 rotatably mounted on the bracket arm 15 engages the eccentric or pattern cam 13 at all times. The engagement between the cam 13 and the roller 14 is 90 maintained by the slidable table 5 through a weight 16 carried by a flexible cable 17 supported by the grooved rollers 18 and 19. The inner end of the cable is secured by means of an eye 20 to an end of the table. 95 Instead of the weight 16 and cable 17 a spring may be employed mounted between the side frame 1 and the other end 21 of the slidable table 5.

A gear 22 is mounted for rotation on the 100 shaft 7 and centrally of the table 5. Said gear is in mesh with a gear 23 which is mounted in bearing 24 on the end 21 of said table.

Connected with the gear 23 is a shaft 25 105 which is slidable in bearings on a bracket 28 which forms an extension of the side frame 1. The bracket provides a support for the usual conventional form of drive mechanism which is commonly employed in lathes. The 110 shaft is provided with a feather 25^a for furnishing a sliding connection between the

driving gear 26 and said shaft. Gear 26 is in mesh with a gear 26^a rigid with a counter shaft 26^b. A cone pulley 27 is driven in the usual manner for driving a gear 27^a.
 5 A gear 26^c driven by a shaft 26^b is adapted to mesh with the gear 27^a.

A bracket arm 29 is slidably mounted on the upper transverse bar 30 which connects the upper ends of the legs 1 and 2 and is 10 vertically adjustable transversely of the said bar by means of a bolt 31 secured to said transverse bar and a slot 32 formed in the upper end of said arm. A roller 33 mounted for rotation at the lower end of 15 said arm is adapted to engage the work and maintain said work in position on the face plate 12.

An arm 34 pivoted at 35 on the transverse bar 30 is adapted to provide means for adjusting a cutter 36 in a plurality of different positions. Said arm 34 is adapted to be adjusted through an arc of a circle by means 20 of bolts 37 and an arcuately shaped slot 38 formed in the enlarged free end 39 of the 25 arm.

Slots 40 formed longitudinally of the arm 34 are adapted to provide a track for receiving a rearward extension of a plate 41 for guiding said plate longitudinally of the 30 arm 34. A hand wheel 42 connected with a screw is adapted to be rotated for adjusting the plate 41 longitudinally of the arm 34. Connected with the plate 41 is a tool holder 43 having a groove 44 for receiving a slide 45 which carries the tool 36. The slide 45 is adjustable transversely of the work holder 43. The cutter 36 is adapted to be locked in 35 rigid position by means of a bolt 46. The holder 43 is adjusted vertically and transversely of the arm 34 by means of a hand wheel 47 connected with the usual screw for the purpose.

When the shaft 25 is operated, gear 23 and likewise gear 22 will be operated for 40 rotating the driven shaft 7. The face plate 12 and the eccentric or pattern cam 13 are likewise driven. Since the pattern cam 13 is of an oval or elliptical shape and is always maintained in engagement with the roller 14 by the weight 16, the table 5 will be reciprocated back and forth when the major axis of the eccentric cam is in contact with the roller 14 and since the table 5 is reciprocated the rotating face plate 12 will likewise 45 be reciprocated. In this manner the cutter, which is in engagement with the work mounted on face plate 12, will operate to form an elliptical pattern of the work mounted on said table. It will be seen that 50 the cutter 36 is adapted to be adjusted in a plurality of different positions so that said cutter is adapted for use in cutting a variety of patterns.

Figure 5 discloses a form 50 made of 55 wood, while a metal form 51 is shown in

Figure 6 upon which the crowns of the hats are made. The forms are adapted to be turned out on my improved lathe.

An annular head plate 52 has an annular depending rib 53 which is adapted to fit into 70 an opening 54 of the cooperating head plate 55. The diameter of the outer periphery of said rib is such as compared with the diameter of the head plate 55 to permit the material of the crown of a straw hat to be located therebetween. The plates are employed when the head of the hat is being sized. The plates are turned out by my lathe.

Figure 10 discloses a die into which the 80 hat is shaped to form under hydraulic pressure and comprises a crown shaping member 56 and a brim shaping member 57. A ring 58 adapted to be seated within the recess 59 may be made of various sizes corresponding 85 to the various sizes of brims and is adapted to maintain the contour of the brims.

What I claim is:

1. In a lathe for turning and boring castings or patterns to the shape on the lower 90 end of a spindle, a frame provided with tracks, a drive shaft mounted on the frame, a table slidably mounted on the tracks, a driven shaft mounted on the table, means connecting the drive shaft with the driven 95 shaft, a work holder on one end of said driven shaft, an eccentric or pattern cam on the other end of the shaft, a roller having a fixed position in engagement with the pattern cam, and means for maintaining the 100 pattern cam in engagement with the roller, and a cutting tool adjustably mounted in operative relation with the work holder.

2. In a lathe, a frame provided with 105 tracks, a drive shaft mounted on the frame, a table slidably mounted on the tracks, a driven shaft mounted on the table, a work holder on one end of the shaft, an eccentric or pattern cam on the other end of the shaft, a gear having a slidable connection with the 110 drive shaft and mounted on the table, a gear mounted on the driven shaft and in mesh with the first mentioned gear, a cutting tool adjustably mounted in operative relation 115 with the work holder, and means engageable with the pattern cam for causing shifting of the table, and means for maintaining the pattern cam in engagement with the last mentioned means.

3. In a lathe, a frame provided with 120 tracks, a drive shaft mounted on the frame, a table slidably mounted on the tracks, a driven shaft mounted on the table, a work holder on one end of the shaft, an eccentric or pattern cam on the other end of the shaft, a gear having a slidable connection with the 125 drive shaft and mounted on the table, a gear mounted on the driven shaft and in mesh with the first mentioned gear, a cutting tool adjustably mounted in operative rela- 130

tion with the work holder, and means engageable with the pattern cam for causing shifting of the table, and means for maintaining the pattern cam in engagement with the last mentioned means, means for maintaining the work in position relative to the cutting tool.

4. In a lathe, a frame provided with tracks, a drive shaft mounted on the frame, a table slidably mounted on the tracks, a driven shaft mounted on the table, a work holder on one end of the shaft, an eccentric or pattern cam on the other end of the shaft, a gear having a slidable connection with the drive shaft and mounted on the table, a gear mounted on the driven shaft and in mesh with the first mentioned gear, a cutting tool adjustably mounted in operative relation with the work holder, means engageable with the pattern cam for causing shifting of the table, means for maintaining the pattern cam in engagement with the last mentioned means, means for maintaining the work in position relative to the cutting tool, and means for adjusting the last mentioned means for maintaining the work in position.

5. In a lathe, a frame provided with tracks, a drive shaft mounted on the frame, a table slidably mounted on the tracks, a driven shaft mounted on the table, means flexibly connecting the drive shaft with the driven shaft, a work holder on one end of said driven shaft, an eccentric or pattern cam on the other end of the shaft, a roller having a fixed position in engagement with the pattern cam, means for maintaining the pattern cam in engagement with the roller, a cutting tool adjustably mounted in operative relation with the work holder, and means for locking the sliding table against oscillating movement.

6. In a lathe, a frame provided with tracks, a drive shaft mounted on the frame, a table slidably mounted on the tracks, a driven shaft mounted on the table, a work holder on one end of the shaft, an eccentric or pattern cam on the other end of the shaft, a gear having a slidable connection with the drive shaft and mounted on the table, a gear mounted on the driven shaft and in mesh with the first mentioned gear, a cutting tool adjustably mounted in operative relation with the work holder, means engageable with the pattern cam for causing shifting of the table, means for maintaining the pattern cam in engagement with the last mentioned means, and a rotatable

means for engaging the work adapted to have a fixed position relative to the rotation and oscillation of the work holder.

7. In a lathe, a frame provided with tracks, a drive shaft mounted on the frame, a table slidably mounted on the tracks, a driven shaft mounted on the table, means flexibly connecting the drive shaft with the driven shaft, a work holder on one end of said driven shaft, an eccentric or pattern cam on the other end of the shaft, a roller having a fixed position in engagement with the pattern cam, means for maintaining the pattern cam in engagement with the roller, a cutting tool adjustably mounted in operative relation with the work holder, and means for adjusting the cutting tool longitudinally of the frame, means for adjusting the cutting tool in an arc of a circle, and means for adjusting said tool vertically of the frame.

8. In a lathe, a frame provided with tracks, a drive shaft mounted on the frame, a table slidably mounted on the tracks, a driven shaft mounted on the table, means flexibly connecting the drive shaft with the driven shaft, a work holder on one end of said driven shaft, an eccentric or pattern cam on the other end of the shaft, a roller having a fixed position in engagement with the pattern cam, means for maintaining the pattern cam in engagement with the roller, a cutting tool adjustably mounted in operative relation with the work holder, means for adjusting the cutting tool in an arc of a circle, and means for adjusting said tool vertically of the frame.

9. In a lathe, a vertical frame provided with tracks disposed in a vertical plane, a drive shaft mounted on the frame, a vertically disposed table slidably mounted on the tracks, a driven shaft mounted transversely of the table and vertically of the frame, a work holder on one end of said shaft, an eccentric or pattern cam on the other end of said shaft, means engageable with the pattern cam for causing shifting of the table, means for maintaining the pattern cam in engagement with the last mentioned means, a gear on the driven shaft, a gear mounted in bearings on the table in mesh with the first mentioned gear and having a sliding connection with the drive shaft, and a cutting tool adjustably mounted in operative relation with the work holder.

WALTER CALEB THATCHER.
